UNITED STATES PATENT OFFICE.

PETRUS VAN SANTEN KOLFF, OF MOYLAN, PENNSYLVANIA, ASSIGNOR, BY MESNE ASSIGNMENTS, TO THE ELECTRIC TACHOMETER CORPORATION, A CORPORATION OF DELAWARE.

MAGNETO-GENERATOR.

1,193,270.

Specification of Letters Patent.

Patented Aug. 1, 1916.

Application filed September 14, 1914. Serial No. 861,544.

To all whom it may concern:

Be it known that I, PETRUS VAN SANTEN KOLFF, a citizen of the United States, residing at Moylan, in the county of Delaware,

5 State of Pennsylvania, have invented certain new and useful Improvements in Magneto-Generators, of which the following is a specification.

My invention broadly stated relates to 10 means for varying and controlling the strength of current delivered from a magneto generator and it has for its object to provide an improved construction of means whereby such variation and control of current delivered from the generator may be 15 effected.

More specifically stated, my invention has for its object to provide an improved construction of means whereby the poles of a 20 magnet may be adjusted toward and from the revoluble armature of the generator, such adjustments causing variations in the current generated and delivered.

In order that my invention may be more 25 readily comprehended and understood reference should be had to the accompanying drawing in which I have illustrated one form of a convenient embodiment of my invention but it will be understood that 30 changes in the details of construction may be made within the scope of the claims without departing from my invention.

In the drawings:—Figure 1 is a transverse sectional view of the casing and inclosed 35 parts of the generator embodying my invention; and Fig. 2 is a horizontal sectional view of a portion of the said device, parts of said device being broken away and omitted.

Referring to the drawings, 1 designates 40 what may be termed the body portion of the casing of a magneto, the open top of which is closed by means of the cover 2, the latter being secured to the top edge of the body portion of the casing by means of screws 3. 45 The body part 1 and the cover 2 consist of brass or other non-magnetic material and together constitute the complete casing. In order to insure that the joint between the abutting edges of the body and top or cover 50 portions 1 and 2 of the casing shall be watertight I provide a washer 4 of suitable material such as fiber which is interposed between the said edges.

For the purpose of securing the magneto 55 upon a wall or other suitable supporting

structure I have provided the body portion thereof at its base or bottom with lugs 5 having holes therethrough through which securing screws or bolts may be inserted.

6 designates a permanent magnet of horse-shoe type, the poles 7 and 8 of which are situated upon opposite sides of and partially surround an armature 10 of any suitable known construction which is supported upon a revoluble shaft 11 sustained in any known 65 manner.

The magnet 6 is supported and held in position by means of vertical flanges 70 which project inwardly from two opposing walls of the part 1 of the magneto casing. 70 There are two of these projecting flanges upon each opposing wall and they are spaced from each other distances equal to the width of the end portions or poles of the magnet so that such end portions may be positioned 75 between and sustained by the said flanges, as illustrated in the drawings.

For the purpose of varying and controlling the current which is delivered from the generator I provide means for adjusting the 80 poles 7 and 8 of the magnet 6 toward and from the armature 10 which means may be described as follows: The pole portions or sections of the magnet are of arc shape the inner sides of the said arcs subtending opposing portions of the armature. The outer sides or surfaces of the pole portions of the magnet are also curvilinear or arcuate in shape, as is clearly indicated in Fig. 3 of 85 the drawings. 72 designates blocks of brass or other non-magnetic material which are situated in the space between the walls of the magneto casing and the arcuate or curvilinear pole portions of the magnet. These blocks are situated above a horizontal plane 90 passing through the curvilinear pole portions of a magnet at the point of greatest distance through the said portions. These adjusting blocks 72 are secured to the screw-threaded ends of bolts 73 of brass or other 95 non-magnetic material the heads of which are situated outside of and rest against a metallic plate or bar 74 of soft iron or equivalent material which is seated against the bottom or base of the part 1 of the casing. By turning these screw-threaded bolts 73 the block 72 may be adjusted in one 100 direction or the other depending upon the direction in which the bolts 73 are turned.

If turned in a direction to cause the poles 7 11

- and 8 to approach each other and thereby reduce the air gap or space between the said poles and armature the number of lines of magnetic force which are cut or interrupted by the revolving armature will be increased. 5 The greater the number of lines of force cut the stronger will be the current which is delivered from the magneto. If, however, the bolts 73 are turned in the opposite direction 10 so as to permit the poles 7 and 8 to move away from each other and thereby increase the air gap or space between the said poles and the armature the number of magnetic lines of force which will be cut by the latter 15 will be reduced with a consequent reduction in the current delivered therefrom. This adjustment may be employed to effect accurate calibration of a milli-volt-meter, or for any other purpose desired. 20 The plate or bar 74 of soft iron or equivalent material is provided as a shield or protector to prevent a change in the flux passing through the armature in case the magnet should be placed or seated upon a magnetic 25 metallic support.

I claim:—

1. In a magneto, the combination of a revoluble armature, a magnet having its poles situated upon opposite sides of the 30 said armature, walls spaced from the poles of said magnet, and adjustable means interposed between the said poles and said walls for adjusting the said poles with relation to the said armature, for the purpose stated.
- 35 2. In a magneto, the combination of a casing having flanges upon opposing sides

thereof, a horseshoe magnet having its poles situated between the said flanges, the said magnet being supported by the said flanges, a revoluble armature interposed between the 40 poles of said magnet, blocks interposed between the poles of said magnet and the opposing walls of said casing, and means for adjusting the said blocks to cause an adjustment of the said poles with relation to the 45 said armature for the purpose stated.

3. In a magneto, the combination of a casing having parallel flanges upon the opposite walls thereof, a magnet of horseshoe type having its poles projected into the 50 spaces between the said flanges and being supported thereby, an armature situated between the said poles, blocks interposed between the opposite poles of said magnet and the opposing walls of said casing intermediate the said flanges, the inner ends of said blocks being beveled and resting against the outer surfaces of the said poles, adjusting screws projecting through the bottom of the said casing and being in engagement with 55 the said blocks for adjusting the same to cause adjustment of the said poles with relation to the said armature, for the purpose stated.

In testimony that I claim the foregoing 60 as my invention, I have hereunto signed my name this 11th day of Sept., A. D. 1914.

PETRUS VAN SANTEN KOLFF.

In the presence of—

FLORENCE DEACON,
CARRIE E. KLEINFELDER.
